UNITED STATES PATENT OFFICE

2,528,609

PROPELLER

Edward H. Rouse, St. Louis Park, Minn.

Application April 8, 1946, Serial No. 660,508

5 Claims. (Cl. 170—160.57)

1

My invention relates to propellers and has for an object to provide a propeller whose pitch may be readily varied to cause the propeller to operate efficiently under various loads.

An object of the invention resides in providing a hub and a number of blades pivotally attached to said hub for swinging movement in a manner to vary the pitch of the blades together with an adjusting member for holding the blades in adjusted position.

Another object of the invention resides in providing an adjustable propeller in which the pitch of the blades throughout the working portions thereof may be varied upon swinging of the blades in a manner to procure the most desirable operating characteristics for the propeller under various loads.

A still further object of the invention resides in providing an adjustable propeller in which the pitch of the blades throughout substantially the entire extent of the working portion thereof may be maintained substantially constant at any adjusted position of the blades.

Another object of the invention resides in providing a construction by means of which adjustment of the blades can be readily made without appreciable difficulty.

A still further object of the invention resides in providing a propeller in which adjustment is positively maintained after having once been made.

Other objects of the invention reside in the novel combination and arrangement of parts and in the details of construction hereinafter illustrated and/or described.

In the drawings:

Fig. 1 is an elevational view of a propeller illustrating an embodiment of my invention and viewed from the aft end of the propeller.

Fig. 2 is a perspective view of the same.

Fig. 3 is a side elevational view of the propeller.

Fig. 4 is an elevational view of the propeller viewed from the tip of one of the blades.

Fig. 5 is a sectional view taken on line 5—5 of Fig. 1.

Fig. 6 is a view similar to Fig. 5 showing the parts in altered position.

Fig. 7 is a sectional view taken on line 7—7 of Fig. 1.

Fig. 8 is a sectional view taken on line 8—8 of Fig. 5.

Fig. 9 is a perspective view of the hub of the propeller with the adjusting nut mounted thereon.

2

Fig. 10 is a diagrammatic view illustrating the relation between the pitches of one of the blades at various localities along the working portion of the same.

Fig. 11 is a plan view similar to Fig. 1 of a modification of the invention.

Fig. 12 is a view similar to Fig. 2 of the form of the invention shown in Fig. 11.

Fig. 13 is a view similar to Fig. 10 showing the relation of the pitches of one of the blades of the propeller illustrated in Figs. 11 and 12.

In variable pitch propellers heretofore designed where the medial line of the blade coincides with the axis of the pivot for the blade,

rotation of the blade through a predetermined angle changes the pitch of the blade appreciably throughout the extent thereof. If, for example, the blade were designed for a five inch pitch throughout the extent of the working portion thereof and the said blade were rotated to procure a pitch of three inches at the tip of the blade, the pitch near the shank of the blade would not change proportionally and would have a pitch of considerably greater than the desired three inches.

The instant invention provides a construction whereby when different load requirements are met, the blades can be swung about their pintles so that the pitch of the blades is varied along the extent thereof in a manner such that the blades operate in an efficient manner under all load conditions to which the propeller is to be subjected.

My improved propeller comprises a hub 10 to which are adjustably attached two propeller blades 11 and 12. Since these blades are identical in construction, only the blade 11 will be described in detail and the same reference numerals, preceded by the digit "1," will be used to represent corresponding parts of the blade 12. The propeller illustrated is a left hand propeller, rotating in a counter-clockwise direction as viewed in Fig. 1.

The hub 10, as best shown in Figs. 5 and 9, comprises a neck 13 having a head 14 formed at the upper portion of the same. The neck 13 is constructed with threads 15 which extend up to within a short distance of the head 14 and where the same are cut back as designated at 16. The head 14 is in the form of a flange, being somewhat larger in diameter than the neck 13 and is provided with two planform surfaces 17 and 18 which serve a purpose to be presently more fully described. The hub 10 is formed with a bore 19 through which the propeller shaft with which the propeller is to be used may extend.

For the purpose of illustration, I have shown in the drawings a propeller shaft 21 having a reduced end 24 which fits within the bore 19. This construction provides a shoulder 22 which is received in a recess 23 formed in the lower end of the hub 10. A pin 27 extends through the shaft 21 at the locality of the shoulder 22 and is received in notches 28 formed in the hub 10. The reduced portion 24 of the shaft 21 is provided with threads 25 on which is screwed an acorn type nut 26 for holding the hub attached to the shaft.

The blade 12 is constructed with a tip portion 29, a working portion 31 and a shank portion 32. The said blade has a trailing edge 61 and a leading edge 62. The shank portion 32 issues from an attaching member 33, the said parts being constructed integral. The attaching member 33 is provided with two bearings 34 and 35, which are disposed opposite one another and which straddle the head 14 of hub 10. The bearing 34 lies opposite the surface 17 of head 14, while the bearing 35 lies opposite the surface 18 of head 14. Extending through the head 14 of hub 10 is a hole 36 which is disposed on one side of the bore 19. The bearing 34 has a similar hole 37 which aligns with the hole 36, while the bearing 35 has a corresponding hole 38 extending into the same. The hole 38 is a blind hole, while the holes 36 and 37 extend completely through the respective parts in which they are formed. A pintle 39 extends through the holes 37 and 36 and into the hole 38 and forms a pivot for supporting the blade 11 during operation for swinging movement from a position shown in dotted lines in Fig. 3 to a position shown in full lines in said figure.

The blade 12 is similarly constructed and supported, being mounted on the pintle 139 which is received in the hole 136 formed in head 14 on the side of the bore 19 opposite the hole 36.

The attaching member 33 is so constructed that a lip 41 is formed on the same adjacent bearing 35 and which lip overlies the end of the pintle 139. By means of this construction, the pintle is held in position and prevented from becoming disengaged from the propeller during the operation of the same. When the blades are assembled, one blade, say blade 11, is first applied and pintle 39 inserted into the holes 37, 36 and 38. The blade 12 is then applied and blade 11 swung to a position beyond that shown in dotted lines in Fig. 3 so that lip 41 uncovers the hole 137. Pin 139 may now be applied.

Adjustment of the propeller is procured by manually swinging the blades 11 and 12 about the pintles 39 and 139. The blades are held in adjusted position through the thrust exerted against the same by the fluid in which the blades operate. This position is determined by means of a construction disposed within the attaching members 33 and 133. This construction consists of a nut 42 formed with threads 43 which are screwed upon the threads 15 of the hub 10. The lowermost end of the nut 42 has a knurled portion 44 by means of which the same may be manually manipulated. Beyond this knurled portion, two slots 45 and 145 are formed in the nut which provide two outstanding portions 47 and 48 spaced from one another. These portions have end walls 49 and 149 which serve a purpose to be presently described in detail. The ends of the slots 45 and 145 form shoulders 51 and 151 on the knurled portion 44 of the nut which shoulders are preferably shaped to incline inwardly toward the axis of the hub, as shown in Figs. 5, 6 and 9.

The attaching member 33 of blade 11 has formed on it a lug 52 which has a cam surface 53 adapted to engage the shoulder 51 on nut 42. The said lug is received within the slot 45 and the sides of the said lug are adapted to engage the end walls 49 of the outstanding members 47 and 48. By means of this construction, the nut 42 is held from rotation. It will readily be comprehended that advancing the nut 42 along the hub 10 will cause the shoulders 51 and 151 to engage the surfaces 53 and 153 of the blades 11 and 12 at different localities in a manner to hold the said blades in different angular positions with reference to the axis of the shaft 21, as indicated in Fig. 3.

For the purpose of protecting and shielding the nut 42 and the hub 10, the attaching member 33 is provided with a shield portion 39 which extends about and partly covers the forward portion of the nut 42.

Where a propeller is desired in which the pitch remains the same throughout the extent of the working portion of the blade upon various adjustments of the blade for pitch alteration, the blade is constructed as shown in Fig. 1. In this figure, the median line of the blade is indicated at 54. This line is determined by drawing various arcs 55, 56 and 57 through the blade with the axis 58 of the shaft 21 as center. The lengths of the arcs 55, 56 and 57 between the trailing edge 61 and the leading edge 62 are bisected and the points 63, 64 and 65 are procured. Line 54 is drawn through these points. I have found that when the line 54 along the working portion 31 of the plate is parallel to a plane indicated at 66 which contains the axis 58 and is at right angles to the axis of the pintles 39 and 139 and when the entire working surface of the blade is situated within the space between this plane and a plane 67 at right angles thereto and containing the axis 58, that angular movement of the blade about the axis of the pintle 39 produced the same changes in the pitch of the blade throughout the working portion thereof. In other words, if the blade were designed to have a five inch pitch throughout its extent when in the position shown in dotted lines in Fig. 3 and the same were adjusted to procure a three inch pitch by shifting the same to the position shown in full lines in Fig. 3, the pitch would then be three inches throughout the entire extent of the working portion of the blade. This will readily become apparent from Figs. 1, 2 and 10. In Fig. 10, I have drawn three triangles 71, 72 and 73 in which the bases 74, 75 and 76 are proportional to the circumferences of the circles whose arcs are indicated at 55, 56 and 57 in Fig. 1 and which have the radii 77, 78 and 79 respectively. The altitudes 81, 82 and 83 of these triangles (Fig. 10) have also been drawn proportional to the pitch of the blades at the points 63, 64 and 65 where the arcs 55, 56 and 57 intersect the median line 54 when the blade is positioned to procure maximum pitch. Since the pitch of the blade at the various localities specified is constant, then altitudes will all be equal. These triangles have been transferred to Figs. 1 and 2 and lie in planes parallel to the axes 58 of the propeller shaft 21 and at right angles to the radii 77, 78 and 79. The altitudes of these triangles contain the points 63, 64 and 65 previously referred to. By projecting the triangles 71, 72 and 73 on a plane containing the median line 54 and parallel to the axis 58, other triangles 84, 85 and 86 are formed (Fig. 2) which have bases 87, 88 and 89 and hypotenuses 91, 92 and 93, the alti-

tudes for the corresponding triangles being the same. The projection of these triangles on the plane 54 produces other triangles 94, 95 and 96 illustrated in Fig. 1, whose hypotenuses are the lines 74, 75 and 76 and whose altitudes are 215, 216 and 217. The bases of these triangles are the bases 87, 88 and 89 of the triangles 84, 85 and 86 (Fig. 2). By erecting construction lines 97, 98 and 99 from the points 63, 64 and 65 perpendicular to the plane 66, other triangles are formed which are indicated at 101, 102 and 103. These triangles have the radii 77, 78 and 79 as hypotenuses and portions of the line 66 for altitudes. The bases of these triangles will be the construction lines 97, 98 and 99. It will be noted that the sides of the triangles 94, 95 and 96 are at right angles to the sides of the triangles 101, 102 and 103. The corresponding triangles are hence similar. Since the bases of the triangles 101, 102 and 103 are equal, the bases 87, 88 and 89 of the triangles 94, 95 and 96 are also equal. These bases being the bases of the triangles 84, 85 and 86, the said triangles are themselves equal. If now the blade 11 be assumed to be rotated about pintle 39 through a certain angle, each of the hypotenuses 91, 92 and 93 would rotate through an equal angle which has been represented in Fig. 2 by the shaded portions of the projected triangles 84, 85 and 86. Since these triangles are all equal, the reduction in the altitudes 81, 82 and 83 is the same and the pitches of the blade at the points 63, 64 and 65 are now reduced but are still equal. Thus, with my invention, the blade when adjusted can be made to procure different pitches which however remain the same throughout the working portion of the blade at any one setting of the same.

The procedure adapted with reference to the points 63, 64 and 65 also applies to any other series of points on the blade 11 parallel to plane 66. It is apparent that the further around the arcs 55, 56 and 57 that points 63, 64 and 65 are located with respect to plane 66, the larger the projections 87, 88 and 89 of the bases of the pitch triangles 74, 75 and 76 will be. Therefore, the greater the pitch variation for a given angle of displacement of blade 11. To secure more pitch variation per given angular displacement of the blades, but still maintain equal pitch variation throughout the working portion of the blade, the blade must be so shaped that median line 54 is still parallel to plane 66 but further therefrom.

It frequently becomes desirable to slightly alter the pitch along the working surface of the blade from shank to tip, for example, to make the pitch greater at the shank of the blade and lesser at the tip of the blade to compensate for the additional slip of the portions nearest the hub when operating under heavy thrust. A blade operating at high pitch and light thrust would have a pitch practically constant over the entire length of the blade from the shank to the tip, whereas the same blade when changed to operate at a lower pitch but with a higher thrust, the pitch should be less at the tip than at the shank. In Figs. 11, 12 and 13, I have shown a propeller designed with these characteristics. Inasmuch as the propeller and the various parts thereof are the same as illustrated in the other form of invention, the description will not be repeated but the same reference numerals with the letter "a" added thereto used to denote corresponding parts. It will be noted in Figs. 11 and 12 that the pitches of the blade at the designated localities are all the same for the high pitch setting of the blade. However,

when the blade is swung through the displacement angle represented by the shaded area, the pitches become different, the remaining pitch nearest the shank of the blade being the greatest. This is accomplished by setting the blade 11a with respect to pintle 39a so that its median or average line 54a (Figs. 11 and 12) is at an angle to plane 66a. By this means it is possible to secure a greater pitch change at the tip than at the shank and thus compensate for additional slippage of the central portion of the working section of the blade 11 as increased thrust is demanded of it as pitch is reduced.

In the design of propeller blades it becomes desirable to increase the pitch at the trailing edge as compared to the pitch at the leading edge. This increase is preferably greater for low pitch blades working under high thrust than for high pitch blades working under low thrust. With my invention, this result is procured since the trailing edge is nearest the plane 66 and decrease of the pitch of the blade by rotating it on its pintle will reduce the pitch nearest the line 66 less rapidly than farther from said line as previously explained.

I have found in the development of my invention that the working portion of the blade should be wholly confined to the space between the planes 66 and 67. Also, I have found that the median line 54 is best located nearer the plane 66 than the plane 67 and that said line be either parallel to or form a slight angle with the plane 66 in accordance with the characteristics of the blade desired. For ordinary use, an angle of approximately 15 degrees between median line 54a and plane 66a is quite suitable.

Where different pitches are desired along the median line, a curved median line will be used instead of a straight line.

While I have described the invention as adapted for use in water, it can readily be comprehended that the propeller may also be used in air, and that the same will give the desired results regardless of the medium in which it is used.

The advantages of my invention are manifest. The propeller is extremely simple in construction and can be readily adjusted. A propeller constructed in accordance with my invention operates efficiently at all of the adjusted positions at which the same may be set within the range of adjustment of the blades. The same propeller can be used for light loads traveling at relatively high rate of speed and for heavy loads traveling at a lower rate of speed. Thus, a single propeller can be furnished for a specified motor which propeller can be adjusted to meet all load requirements.

Changes in the specific form of my invention, as herein described may be made within the scope of what is claimed without departing from the spirit of my invention.

Having described my invention what I claim as new and desire to protect by Letters Patent is:

1. In a propeller, a hub, a swinging blade carried thereby, an attaching member at the inner end of the blade, pivot means acting between said attaching member and hub and disposed in proximity to the axis of said hub, said pivot means having its axis at right angles to a plane containing the axis of said hub, a part of the median line of said blade at the outermost portion thereof being disposed within the space between said plane and a plane containing the axis of the hub and at right angles to the first plane, said portion of the median line of the blade forming

an outwardly diverging angle of between 12° and 15° with said first plane said portion of the median line if extended intersecting the first named plane outwardly of said hub.

2. In a propeller, a hub, a swinging blade carried thereby, an attaching member adjacent said hub and from which said blade extends, pivot means for the blade acting between said attaching member and hub and disposed in proximity to the axis of said hub, said pivot means having its axis at right angles to a plane containing the axis of said hub, axially progressing threads formed on the exterior of said hub, a nut screwed on said threads and having a beveled shoulder, a lug on said attaching member engaging said shoulder to hold the blade in adjusted angular position, and an outstanding portion on said nut providing a wall for engaging said lug to restrain rotational movement of the nut.

3. In a propeller, a hub, a swinging blade carried thereby, an attaching member adjacent said hub and from which said blade extends, pivot means for the blade acting between said attaching member and hub and disposed in proximity to the axis of said hub, said pivot means having its axis at right angles to a plane containing the axis of said hub, axially progressing threads formed on said hub, a nut screwed on said threads, a shoulder on said nut, a projecting part on the attaching member for engagement with said shoulder to hold the blade in adjusted angular position, and an outstanding portion on said attaching member having a wall for engaging and locking said nut for rotation.

4. In a propeller, a hub, a swinging blade carried thereby, an attaching member adjacent said hub and from which said blade extends, pivot means for the blade acting between said attaching member and hub and disposed in proximity to the axis of said hub, said pivot means having its axis at right angles to a plane containing the axis of said hub, axially progressing threads

formed on said hub, a nut screwed on said threads, a manipulating portion on the nut, a slot formed in said nut beyond the manipulating portion and providing at the end of the same a shoulder and on each side thereof axially projecting portions, a lug on said attaching member adapted to enter said slot when the blade is swung in one direction and to seat against said shoulder, said lug being engageable with said axially projecting portions to restrain turning of the nut.

5. In a propeller, a hub, a plurality of swinging blades carried thereby, an attaching member for each blade, said attaching members having spaced bearings receiving said hub, one of the bearings of each blade and the hub having aligning through holes, the other of said bearings having blind holes communicating with and in alignment with the corresponding holes in the hub, pintles in said holes for supporting said blades for swinging movement relative to said hubs and a lip on each of the bearings having the blind holes and adapted in certain positions of the blades to overlie the exposed ends of the 20 25 pintle of the juxtaposed blade.
